Des. 240,094
Patented June 1, 1976

240,094

BELT-ATTACHED CAMERA CARRIER

Arnoldo D. Linn and Berta Cortes, both of 2046
Greenwich St., San Francisco, Calif. 94123

Filed Nov. 21, 1974, Ser. No. 526,025

Term of patent 14 years

Int. Cl. D2—07

U.S. Cl. D2—400

FIG_1

FIG_2

FIG_3

FIG_4

FIG_5

FIG_6

FIG_7

FIG. 1 is a right front perspective view of a belt-attached camera carrier showing our new design;

FIG. 2 is a left front perspective view thereof;

FIG. 3 is a top plan view thereof;

FIG. 4 is a front elevational view thereof;

FIG. 5 is a right side elevational view thereof;

FIG. 6 is a bottom plan view thereof; and

FIG. 7 is a rear elevational view of a belt-attached camera carrier.

We claim:

The ornamental design for a belt-attached camera carrier, as shown and described.
